UNITED STATES PATENT OFFICE

RICHARD W. RANDALL AND JOHN C. KOCH, OF STOCKTON, CALIFORNIA

TUBE CLEANER

Application filed December 15, 1930. Serial No. 502,476.

This invention relates to tools for cleaning scale and other encrustations from the interior of tubes and pipes, and particularly to a tool for the purpose of the rotative type with which the removal of the encrusted matter is effected by a relatively rapid rotation of the tool accompanied by an advance of the same lengthwise of the tube.

The principal object of our invention is to provide a tool of this general character so constructed that the cutting elements of the tool move through an arc eccentric to the axis of rotation of the tool and will be thrown against and held engaged with the walls of the tube solely by a yielding centrifugal force. The tool may thus be effectively used in tubes regardless of whether they are true or out of round, and there is also no danger of any seams, rivet heads, or the like which may be encountered being cut into, or the cutting elements themselves damaged by such contact.

A further object of the invention is to provide a simple and inexpensive device and yet one which will be exceedingly effective for the purpose for which it is designed.

These objects we accomplish by means of such structure and relative arrangement of parts as will fully appear by a perusal of the following specification and claims.

In the drawing similar characters of reference indicate corresponding parts in the several views:

Fig. 1 is a side elevation of our improved cleaner as in operation.

Fig. 2 is an end view of the same.

Fig. 3 is a fragmentary section showing the mounting of a cutting element.

Referring now more particularly to the characters of reference on the drawing, the numeral 1 denotes a body of relatively heavy material and which is preferably of oblong form with rounded ends and rectangular in cross section. Fixed in and projecting from one face of the body toward its ends are headed spindles 2 on which are turnably mounted sharp-toothed cutting discs 3. These discs have different numbers of teeth so that the teeth of one will not track in the grooves made by the other with the rotation

of the tool. The teeth of course are disposed so that they project beyond the ends of the body, so that they will engage the walls of the tube and the encrustations thereon without interference from the body.

The diametral distance between the outermost opposed teeth of the two discs is less than the internal diameter of the tube 4 being operated on, so that the two discs always engage the tube to one side of the diametral plane of the same, and both spindles are likewise disposed to one side of such plane, as shown in Fig. 2.

A shaft adapted to be driven by any suitable means, preferably a flexible shaft connected thereto, from outwardly of the tube, is connected to the body to turn the same. This shaft comprises an outer end portion 5 which is maintained in central axial alignment with the axis of the tube, and which is symmetrically disposed relative to the spindles; and a relatively long angularly disposed portion 6 which extends and is rigidly secured to the face of the body opposite to that on which the discs are mounted. The point of connection of said angular portion with the body is preferably adjacent the axis of one of the spindles 2, as indicated in Fig. 1, so that with the rotation of the shaft the weight of the body will exert a relatively great centrifugal or whipping effort.

As a result of this arrangement both discs remain engaged with the tube as the shaft rotates, cutting out the encrusted matter 7 as the shaft is advanced lengthwise in the tube. The pressure of the cutting discs against the tube is governed by the centrifugal action had by reason of the weight of the body and its offset connection with the shaft, and also to the fact that the shaft is not rigidly secured in the tube. The disc and body may therefore yield radially of the tube if the same is out of round, or if metal protrusions, such as seams or rivet heads, project inwardly of the tube. No damage is therefore done to such protruding parts or to the cutters themselves.

From the foregoing description it will be readily seen that we have produced such a

device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described our invention what we claim as new and useful and desire to secure by Letters Patent is:

1. A tube cleaner adapted to be introduced into a tube comprising a drive shaft adapted to be disposed concentrically in said tube and having a portion extending at an angle to the remainder of said shaft, a body at the end of said portion symmetrically disposed relative to a plane passing through the shaft and to which the outer end of said portion is secured, and cutting elements projecting outwardly of the side edges of the body mounted thereon in opposed relation to each other.

2. A tube cleaner comprising a drive shaft having a main portion and having at one end a portion extending at an angle to said main portion, a body at said end symmetrically disposed relative to a plane passing through said shaft and to which the outer end of said extending portion is secured, rotary cutters disposed on one face of the body and of a diameter to project outwardly of the peripheral edges of the body, and axial supports for the cutters mounted in the body parallel to the shaft.

3. A structure as in claim 2, in which one of said supports is aligned with the connection of the extending portion of the shaft with the body, while the other support is located a corresponding distance on the other side of said plane.

4. A tube cleaner comprising a drive shaft adapted to extend centrally and coaxially into a tube, a body, spindles mounted on one face of the body parallel to the axis of said tube and in symmetrical relation to a plane passing through the axis of said tube and to one side of a second axial plane perpendicular to said plane, rotary cutters mounted on the spindles to project outwardly of the edges of the body so as to engage the walls of the tube to one side of said second axial plane, and a portion of the shaft diverging from the axis of said tube and secured at its outer end on the body.

5. A tube cleaner comprising spaced rotary cutters to engage the walls of a tube, the diametral distance between the opposed edges of the cutters being less than the diameter of the tube, a body on which said cutters are turnably mounted, a shaft adapted to extend centrally in the tube and parallel with the axes of rotation of the cutters, and means connecting the shaft to the body to maintain the cutters to one side of the diametral plane of the tube with the rotation of the shaft.

6. A tube cleaner comprising spaced rotary cutters to engage the walls of a tube, the diametral distance between the opposed edges of the cutters being less than the diameter of the tube, a body on which said cutters are turnably mounted, and means to rotate the body about a center spaced from said body so as constantly to maintain the cutters to one side of the diametral plane of the tube.

7. A tube cleaner comprising a drive shaft, a body mounted on said shaft, and a pair of cutters mounted to rotate on and with respect to said body on axes parallel to the axis of said shaft, both of said cutters being located on one side of a plane passing through said axis.

In testimony whereof we affix our signatures.

RICHARD W. RANDALL. 65
JOHN C. KOCH.
